UNITED STATES PATENT OFFICE.

CORNELIUS L. SHADER, OF GREEN ISLAND, AND JOHN E. FALLE, OF TROY, NEW YORK.

SHIRT-NECKBAND.

1,378,825.

Specification of Letters Patent. Patented May 17, 1921.

Application filed July 16, 1920. Serial No. 396,753.

To all whom it may concern:

Be it known that we, CORMELIUS L. SHADER and JOHN E. FALLE, citizens of the United States, and residents of Green Island, in the county of Albany and State of New York, and Troy, in the county of Rensselaer and State of New York, respectively, have invented an Improvement in Shirt-Neckbands, of which the following is 10 a specification.

Our invention is a neck-band for shirts and its primary object is to provide a neck-band which may be formed from a single pattern and cut in one operation.

15 Secondly, it is the purpose of the invention to provide a neck-band so constructed as to permit the neck of the shirt to be readily inserted therein for stitching and when stitched thereto can not become readily 20 ripped at its ends.

Further, the invention embodies a neck-band which is formed from a single blank folded in such a manner as to produce a neck-band and may be manufactured with a 25 saving of material and labor.

It is a further purpose of the invention to provide a neck-band which when starched and ironed will not cause the plies of the same to adhere but which will space the 30 plies at a point where the rear collar button is inserted so as to facilitate the engagement of the collar button therewith.

With the preceding and other objects as become apparent from the following disclosure, the invention consists in the blank folded and stitched in a manner to be herein-after specified and illustrated in the accompanying drawings wherein,

Figure 1 is an elevation of the blank from 40 which the neck-band is formed;

Fig. 2 is an elevation of the blank after it is folded longitudinally at its center;

Fig. 3 is a similar view of the blank after the second folding operation;

45 Fig. 4 is an elevation of the blank folded on the broken line shown in Fig. 3 and the tongue thereof being inserted in the slot in the body of the blank;

Fig. 5 is an elevation of the blank after 50 the same has been completely folded in the manner disclosed in Fig. 4;

Fig. 6 is an elevation of the blank folded on the broken line shown in Fig. 5;

Fig. 7 is an elevation of the completed 55 neck band after the same has been stitched;

Fig. 8 is an enlarged transverse sectional view taken on line 8—8 of Fig. 2;

Fig. 9 is an enlarged transverse sectional view taken on line 9—9 of Fig. 3;

Fig. 10 is an enlarged transverse sectional view taken on line 10—10 of Fig. 5;

Fig. 11 is an enlarged transverse sectional view taken on line 11—11 of Fig. 6; and

Fig. 12 is an enlarged transverse sectional view taken on line 12—12 of Fig. 7.

Referring in detail to the drawings, wherein like characters designate like parts throughout the several views, the numeral 5 designates an elongated blank of fabric from which the neck-band is fashioned and

is formed with a substantially rectangular tongue 6 at one of its longitudinal edges centrally of its ends. In fashioning the neck band the blank 5 is folded upon its longitudinal center along the broken line 7

as illustrated in Fig. 2. The blank is then creased adjacent one of its longitudinal edges along the dotted line 8 to assume the position indicated in Fig. 3. The opposite longitudinal edge of the blank is folded

upon itself along the line 9 and the tongue 6 folded along the longitudinal line 6' and inserted through the longitudinal slot 10 formed in the blank 5 at its center. This manner of folding the blank affords a pair

of parallel plies of double thickness and between which the neck of the shirt is positioned for stitching thereto. After the

blank has been folded in this manner to afford the superposed parallel plies the free longitudinal edges of the same and its opposite transverse ends are folded inwardly to afford a marginal beading 11

85 which serves to lock the folded parts together as disclosed in Fig. 5. After this 90

operation the blank is folded longitudinally along the longitudinal center line designated at 12 and the longitudinal bead of

one of the plies engaged beneath the longitudinal bead formed upon the free edge of

that ply carrying the tongue 8, these parts being then hemmed along the beaded edge

as indicated at 13 in Fig. 7 securing the

two plies and free end of the tongue together.

100 The plies of the completed neck-band thus forms a pocket for the reception of the shirt-neck and the tongue 8 will prevent these

plies from adhering to each other when the

collar-band is starched and ironed at the

105

110

point where the rear collar button will be positioned, thus the operator may readily separate the plies at either side of the tongue for the insertion of the collar button. Moreover this tongue serves as a pad for this collar button to prevent the same from pressing against the wearer's neck.

The shirt-neck indicated at 14 is inserted between the plies of the neck-band and these 10 plies stitched along their free edges to the opposite ends of the tongue 8 from which points the shirt-neck is stitched directly to the tongue.

It is to be understood that the form of our 15 invention herein shown and described is to be taken as a preferred example of the same, and that various changes in the shape, size and arrangement of parts may be resorted to without departing from the spirit of the 20 invention or the scope of the subjoined claims.

Having thus described our invention, what we claim as new and desire to secure and protect by Letters Patent of the United 25 States, is:

1. A neck-band for shirts including a blank folded longitudinally to afford a pair of plies for the reception of the neck of the shirt, the blank being provided with a longitudinal slot centrally of its ends, and a tongue carried by one edge of the blank and insertible through the slot to space the plies at one point.

2. A neck-band for shirts including a

blank folded longitudinally to afford a pair 35 of plies for the reception of the neck of the shirt, the blank being provided with a longitudinal slot centrally of its ends, a tongue carried by one edge of the blank and insertible through the slot to space the plies at 40 one point, the free marginal edges and the ends thereof being formed with a bead, the bead of one ply being positioned behind the bead of the other and the parts stitched along such beads.

3. As an article of manufacture, an elongated fabric blank formed with an outstanding tongue at one of its longitudinal edges and further provided with a longitudinal slot in transverse alinement therewith, the blank being folded longitudinally adjacent its opposite longitudinal edges to afford a pair of plies of double thickness, and a tongue folded upon itself and inserted through the slot to dispose the tongue between the plies, the plies being formed with longitudinal beads at its free longitudinal edges and at its transverse ends and the bead of one ply engaged behind the bead of the other ply, and said beads stitched together, 60 a shirt-neck inserted between the plies and the latter stitched at their free edges to the opposite ends of the tongue from which points the shirt-neck is stitched to the tongue, the latter spacing the plies at this 65 point and also serving as a pad.

CORNELIUS L. SHADER.
JOHN E. FALLE.
